UNITED STATES PATENT OFFICE.

FRANK E. WILCOX, OF MECHANICSBURG, PENNSYLVANIA.

MEANS FOR ATTACHING BODY-LOOPS TO HANGER-BARS.

1,164,042.

Specification of Letters Patent. Patented Dec. 14, 1915.

Application filed August 22, 1913. Serial No. 786,113.

To all whom it may concern:

Be it known that I, FRANK E. WILCOX, a citizen of the United States, residing at Mechanicsburg, in the county of Cumberland and State of Pennsylvania, have invented certain new and useful Improvements in Means for Attaching Body-Loops to Hanger-Bars, of which the following is a specification.

10 The object of my invention is the provision of improved means for securely and rigidly attaching the ends of vehicle body loops to the ends of hanger bars. Heretofore various means have been devised for 15 the purpose and so designed that they should not work loose under the severe strains to which they would be subjected, but as far as I am aware all such prior means have embodied imperfections of construction and after a short period of time have 20 become loose or split the bars and required repairs or the substitution of parts.

My invention consists in a metallic hanger bar with conical or tapering holes there- 25 through and body loops with perforated tapering heads fitting the tapering holes in the hanger bar and firmly and immovably held within said holes by bolts passed through the heads and nuts on the ends of 30 the bolts, clamping the surfaces in frictional contact.

The accompanying drawing illustrates an example of the embodiment of the invention constructed according to the best mode of 35 procedure I have so far devised for the purpose.

Figure 1 is a view in perspective of a metallic hanger bar, showing at one end a body loop attached thereto by my improved 40 means, the other end showing the parts separated. Fig. 2 is a view in perspective of Fig. 1 as seen from the opposite or rear side. Fig. 3 is a section of the hanger bar and leaves of a supporting spring, the clips being 45 bent down and a yoke applied. Fig. 4 is an enlarged section of Fig. 2 taken through one end of the hanger bar and the head of a body loop.

Referring to the figures, the letter A des-

ignates the metallic hanger bar secured to 50 the spring B by clips C passed through holes in the bar, bent down and yoke D and nuts E applied to the threaded ends of the clips. The clips anchor the bar securely at its central portion.

55

The method of attaching the body loops to the ends of the hanger bar consists in making conical or tapering holes F in the ends of the bar, fashioning tapering heads G at the ends of the body loops H, perforating 60 the said heads at I and forming a tapering seat J at the top end thereof, and then seating the heads in the tapering holes and passing threaded bolts K with tapering heads L through the heads G and ends of the bar 65 and finally clamping the parts together by nuts M on the ends of the bolts.

By the means illustrated and described the body loops are rigidly and immovably anchored to the ends of the hanger bar, the 70 heads will not work loose and the bar will not split.

I am aware of the means for attaching body loops to hanger bars disclosed in Letters Patent issued to W. F. Morton, July 75 30, 1895, No. 543,698, and to F. S. Carr, June 28, 1896, No. 553,668, and other analogous means, and do not claim such devices or combinations.

What I claim as new and desire to secure 80 by Letters Patent is:

The combination of a metallic hanger bar having a plain tapering hole there- 85 through; a body loop with a perforated tapering head at the end, said perforation being enlarged at one end to form a seat; a threaded bolt with a tapering head the plain part of the bolt fitting the plain tapering hole at the smallest diameter and the head fitting the seat in the loop head, and a nut; 90 whereby the turning of the nut will draw the parts into close frictional contact.

In testimony whereof I affix my signature in presence of two witnesses.

FRANK E. WILCOX.
